HERMAN F. PEEPER INVENTOR.

BY

Richard B. Diven ATTORNEY.

UNITED STATES PATENT OFFICE.

HERMAN F. PEEPER, OF APACHE, OKLAHOMA.

SIFTING APPARATUS.

1,411,979.

Specification of Letters Patent. Patented Apr. 4, 1922.

Application filed August 3, 1920. Serial No. 400,908.

To all whom it may concern:

Be it known that I, HERMAN F. PEEPER, a citizen of the United States, residing at Apache, in the county of Caddo and State 5 of Oklahoma, have invented certain new and useful Improvements in a Sifting Apparatus, of which the following is a specification.

This invention relates to an improvement 10 in a sifting apparatus which is particularly designed for use in connection with flour mills, though it may be useful in other connections for its sifting function.

The principal object of the invention is to 15 provide an air circulation means which may be easily attached to any sifter or bolter used in flour mills with very little alterations and expense.

Another object of the invention is to provide 20 a simple and efficient air controlling means which will also aid in controlling the flow of stock.

A further object of the invention is to 25 generally improve upon devices of this nature by providing one which will be extremely simple, durable and inexpensive in construction, one which is efficient and reliable in operation, and well adapted to the purpose for which it is designed.

With these and other objects in view, the 30 invention resides in certain novel features of construction, and the combination and arrangement of parts as will be hereinafter fully described.

35 In the drawing:—

Figure 1 is a fragmentary side elevation of the device, and

Figure 2 is an end elevation thereof showing portions in section.

40 The numeral 1 represents a sifter or bolter of conventional construction which is provided with openings in the top thereof for receiving the stock spout 2 and the cylinders 3 and 4 which are situated at the head

45 and tail of each section of the sifter or bolter respectively. These cylinders 3 and 4 are constructed of cloth or fabric material and are provided at their top portions with the collars 5 having the flanges 6 which are

50 attached to the boards 7 in any suitable man-

ner. These boards 7 may be extended and fastened to any suitable support. It will of course be understood that the function of the boards 7 is to hold the cylinders 3 and 4 in an extended position. Apertures are 55 provided in the boards 7 so as to receive the rods 8 which have mounted upon their inner ends the valve disks 9 so that the circulation of the air may be controlled. It will of course be readily understood that 60 the farther the disk is moved upwardly the greater will be the circulation and vice versa.

With this device as described it will be 65 readily seen that the flow of stock can be regulated causing it to bolt more thoroughly instead of tailing over as would be the tendency without this air circulation.

From the foregoing description, taken in connection with the accompanying drawing, 70 the construction and operation of the device can be readily understood without a more extended explanation. As numerous changes in form, proportion and in the minor details of construction may be 75 resorted to without departing from the spirit of this invention, I do not wish to be limited to the construction herein shown and described other than as claimed.

Having thus described my invention what 80 I claim as new is:—

1. In combination with a sifter, a pair of cylinders constructed of fabric material, means for holding said cylinders in an extended position, and valve means situated 85 within said cylinders.

2. In a sifter, a support, a cylinder formed of fabric material depending from the support, means for holding said cylinder in an extended position, a stem extending through the support and the cylinder and a disc valve mounted on the inner end of the stem so as to be movable longitudinally in the cylinder. 90

In testimony whereof I affix my signature in presence of two witnesses.

HERMAN F. PEEPER.

Witnesses:

J. W. PIERATT,
SLOAN HANCOCK.
